UNITED STATES PATENT OFFICE

JACOB ALONZO DUVALL, OF COLLINSVILLE, OKLAHOMA

COAL BREAKER FOR LOADING MACHINES

Application filed March 13, 1930. Serial No. 435,508.

This invention relates to a coal breaker for attachment to loading machines and more particularly to a device of this character which is adapted to be attached for use on 5 various conventional coal loading machines of the type used in strip mines, but it is to be understood that a breaker constructed in accordance with this invention may be utilized in any manner for which the same is found 10 adapted and on any type of machine.

The primary object of the invention is to provide, in a manner as hereinafter set forth, a coal breaker of the aforementioned character which is adapted to be expeditiously attached to the shiftable shovel or shovel frame of a coal loading machine in a manner to be operated by the movement of said shovel or frame for the purpose of loosening and breaking away the coal which is to be loaded by 20 said machine.

Other objects of the invention are to provide a coal breaker for loading machines of the character set forth which will be simple in construction, strong, durable, efficient in its 25 use and which may be manufactured and installed at low cost.

All of the foregoing and still further objects and advantages of the invention may become apparent from a study of the following specification taken in connection with the accompanying drawing wherein like characters of reference designate corresponding parts throughout the several views, and wherein:—

35 Figure 1 is a perspective view showing a coal breaker constructed in accordance with this invention in operative position and attached to the loading machine for actuation thereby.

40 Figure 2 is a view in elevation of the coal breaker detached from the loading machine.

Referring to the drawings in detail, the reference character 1 designates generally a 45 portion of a conventional coal loading machine which comprises a shovel or scoop 2 rigidly mounted in a supporting frame 3 which is mounted to travel longitudinally on a swingable boom 4. As usual, the shovel supporting frame 3 is actuated to move longitudinally on the boom 4 through the medium of

a rack and gear arrangement, a portion only of which is shown at 5 which designates one of the rack bars mounted on the frame 3. The frame 3 further includes a plurality of cross beams or braces one of which is shown 55 at 6. As will be apparent the loose coal 7 is loaded into the scoop or shovel 2 by swinging the boom 4 in a manner to dispose said shovel on or adjacent to the ground and then move the same forwardly in a manner to scoop the 60 coal thereinto after which the shovel and supporting frame 3 are retracted as the boom 4 swings outwardly to deposit the coal in the vehicle to be loaded.

The device comprising this invention includes an elongated bar 8 formed preferably of iron and of suitable length and diameter. Formed on the opposite end of the bar 8 are the eyes 9 and 10. A threaded eye bolt 11 is engaged through the eye 10 of the bar 8 and constitutes means for anchoring said rod loosely for swinging movement on the cross beam or brace 6 of the shovel supporting frame 3. It is to be understood that the rod 8 may be secured to any other convenient 70 place on the shovel supporting frame 3 if desired. The eye bolt 11 is projected through a whole (not shown) which is provided therefor in the cross beam or brace 6 and a nut 12 is threaded thereon for anchoring the same in 75 said beam.

As clearly seen in the drawings, the rod 8 extends forwardly from the beam or brace 6 to which it is anchored and has loosely connected to its forward end through the medium of the eye 9, a link chain 13 to the free end of which is loosely connected a ring 14 which, in turn, is adapted to be loosely disposed over an inclined peg or stake 15 which is driven into the ground forwardly of the 85 free end of the boom 4, as clearly illustrated 90 in Figure 1 of the drawings.

In use, the rod 8 is anchored to the shovel supporting frame 3 and the stake 15 is driven into the coal at the proper position forwardly of the boom 4. When the shovel is driven 95 forward below the loose coal 7 thereinto and has reached its fully loaded or forwardmost position, the ring 14 is disposed over the stake 15. The frame 3 with the shovel 2 thereon 100

is then retracted and the boom 4 swings outwardly to deposit the coal from the shovel 2 into the vehicle to be loaded. This movement of the frame 3 and boom 4 pulls the stake 15 rearwardly and thus breaks loose the coal into which said stake is positioned. As the stake 15 is pulled rearwardly the ring 14 slips off of the upper end thereof and said stake is left lying loose on the coal, to be picked up by an attendant.

In this manner the coal is loosened in large pieces which constitutes a desirable feature of this invention and this without the necessity of blasting which constitutes the present method of loosening the coal. It will further be seen that this invention will operate efficiently in places where the coal is submerged in water, a condition which offers considerable difficulty when the blasting method of loosening the coal is used.

The stake 15 is disposed at an inclination away from the boom 4 and the insertion of the stake in the coal bed is preferably facilitated by drilling a hole at an inclination in said coal bed into which the stake may be readily inserted.

It is believed that the many advantages of a coal breaker constructed in accordance with this invention will be readily understood, and although the preferred embodiment of the invention is as illustrated and described, it is to be understood that changes in the details of construction may be had which will fall within the scope of the invention as claimed.

What is claimed is:—

1. A coal breaker of the character described comprising a pull rod, a stake adapted to be driven into the coal to be broken and means for connecting the rod to the stake in a manner to pull said stake laterally in the coal.

2. A coal breaker of the character described comprising a pull rod, a stake adapted to be driven into the coal to be broken and means for releasably connecting the pull rod to the stake in a manner to pull said stake laterally and uncouple the rod therefrom.

3. A coal breaker of the character described comprising a pull rod, a stake adapted to be driven into the coal to be broken and a ring connected to the rod and adapted to be mounted around the stake, said ring constituting means for detachably coupling the rod to the stake in a manner to pull said stake to be pulled laterally and release the rod therefrom.

4. A coal breaker of the character described comprising a pull rod, a stake adapted to be driven into the coal to be broken, a flexible chain connected to one end of the pull rod, a ring loosely mounted on the free end of the chain and adapted to be loosely disposed over the stake, said chain and the

ring constituting means for coupling the pull rod to the stake in a manner to permit said stake to be moved laterally and release the pull rod therefrom.

5. A coal breaker of the character described comprising a pull rod, means on one end of the pull rod for securing the same to a draft element, a chain connected to the opposite end of the pull rod, a stake adapted to be driven into the coal to be broken, and a ring mounted on the free end of the chain and adapted to be disposed loosely over the stake in a manner to move said stake laterally upon actuation of the pull rod and release said pull rod therefrom. 75

6. A coal breaker of the character described comprising an elongated pull rod, integral eyes mounted on the opposite end of the pull rod, an eye bolt loosely connected to one of the rod eyes and constituting means for swingably connecting said rod to a draft device, a flexible chain loosely connected to the other eye, a stake adapted to be driven into the coal to be broken and a ring loosely mounted on the free end of the chain for disposition over the stake in a manner to move said stake laterally upon actuation of the pull rod and release said pull rod from the stake. 80

7. In combination with a coal loading machine having a swingable boom and a shovel supporting frame mounted for longitudinal movement thereon, an elongated pull rod, means on one end of the pull rod for anchoring the same to the shovel supporting frame 95 for actuation thereby, a flexible chain loosely connected to the opposite end of the pull rod, a stake adapted to be driven into the coal to be broken and a ring loosely mounted on the free end of the chain for disposition 100 over the stake in a manner to move the same laterally upon actuation of the pull rod in one direction by the shovel supporting frame. 105

In testimony whereof I affix my signature. 110
JACOB ALONZO DUVALL.
